UNITED STATES PATENT OFFICE.

JAMES E. LEWIS, OF STEELTON, PENNSYLVANIA, ASSIGNOR TO THE PENNSYLVANIA STEEL COMPANY, OF PHILADELPHIA, PENNSYLVANIA, A CORPORATION OF PENNSYLVANIA.

RAILWAY CROSSING OR FROG.

No. 832,615.

Specification of Letters Patent.

Patented Oct. 9, 1906.

Application filed February 3, 1906. Serial No. 299,306.

To all whom it may concern:

Be it known that I, JAMES E. LEWIS, a citizen of the United States, residing at Steelton, Dauphin county, State of Pennsylvania, have invented certain new and useful Improvements in Railway Crossings or Frogs, of which the following is a full, clear, and exact description, reference being had to the accompanying drawings, of which—

Figure 1 is a plan view of a crossing or frog in which my invention is embodied, the keys and drifts being omitted for perspicuity. Fig. 2 is a section on line *x* *x*, Fig. 1, with the keys and drifts in place. Figs. 3, 4, and 5 are respectively sections on lines *y* *y*, *z* *z*, and *v* *v*, Fig. 1. Fig. 6 is a perspective of a key. Fig. 7 is a section on line *u* *u*, Fig. 6.

This invention relates to street-railway crossings or frogs in which a hard-metal wear-plate made separate from the base or body of the structure is detachably secured thereto.

The object of the invention is to provide an improved means for thus fastening the wear-plate.

The precise nature of the invention will appear from the following description.

Referring to the drawings, 1 denotes the body or base of a crossing of usual form, and 2 the detachable wear-plate, which rests in a depression 3 of the base.

In carrying out my invention I make in the base a channel 4, that extends from a point in the top of the base to one side of and adjacent to the end of the wear-plate, transversely and downwardly in said base, to the longitudinal middle line of the latter or thereabout, as best seen in Fig. 2. The form of said channel in cross-section is seen in Fig. 5. It is open at one side and at the top and closed at the bottom. The wall 4^a of the channel opposite the open side is cut under or inclined, as seen in said Fig. 5. Opposite this channel 4 is another channel 5, which is open at the side toward the first channel and also at the top and, similarly to the first channel, extends from a point beyond the line of the side of the wear-plate downwardly to the middle line of the latter, as seen in Fig. 2 and indicated by dotted lines in Fig. 3. Between these two channels is an open space that extends from the line of the bottom of said channels to the top of the base 1. Ex-

tending from the opposite side of the wear-plate into the base 1 are channels 6 and 7, 55 which are respectively duplicates of the channels 4 and 5, and there is also an open space between these latter channels similar to that between the first two. The channel 6 is opposite to and its inner end communicates 60 with the channel 4 on the opposite side of the wear-plate, and the channel 5 is opposite to and its inner end communicates with the channel 7 on the opposite side of the wear-plate. The channels 5 and 6 are simply 65 square (in cross-section) recesses within the base for the insertion of drifts whose inner ends abut against keys within the channels 4 and 7, that are similar to each other, all as hereinafter set forth.

Depending from the under side of the wear-plate 2 is a projection 8, one portion of which on one side of the longitudinal middle of the wear-plate is inclined similarly to the incline of wall 4^a of the channel 4, and the 75 portion on the opposite side of the longitudinal middle of the wear-plate is inclined similarly to the corresponding wall of the channel 7, which will of course be the reverse of that of channel 4—that is, both the walls are inclined or undercut into the base 1. When the wear-plate is placed in position in and on the base 1, the said projection 8 (or rather projections, there being in practice usually similar projections and corresponding channels 80 adjacent each end of the wear-plate, as seen) is entered into the before-mentioned space between the channels 4 and 5 and 6 and 7, thereby closing the open sides of said channels, thus forming passage-ways of the channels 4 and 7 of rhomboid form in cross-section, as seen in Fig. 5, and passage-ways of the channels 5 and 6 of rectangular form in cross-section.

Referring to Figs. 2, 6, and 7, 10 is a key 95 which is rhomboidal in cross-section, as seen in Fig. 7, and is tapering on the sides, so as to constitute a wedge, as seen in Fig. 6. This wedge-key (or rather these wedge-keys, there being one for each of the channels 4 and 7) is driven into the channel 4, and a similar key is driven into the opposite passage-way 7. The tendency of one of these keys is to force the projection 8—that is, the wear-plate—in one direction against the vertical 100 wall of the space occupied by said projections,

thus securely holding the wear-plate in place against lateral or vertical displacement.

It is immaterial what the passage-ways 5 and 6 may be in cross-section, as their sole purpose is to receive drifts 11 for driving out the keys when necessary. The said passage-ways 5 and 6 are preferably curvilinear, as seen in Fig. 2, and in each of the same I insert a drift 11, also of corresponding shape. 10 When for any reason it is required to remove the wear-plate, the said drifts are driven in by a suitable tool, so as to eject or loosen the wedge-keys 10, which may then be removed and the wear-plate thus released.

15 After the parts are together and the keys and drifts inserted I would usually pour into the several passage-ways a suitable metal, such as spelter metal, so as to solidify the structure and prevent ingress of rain, and so 20 prevent rusting of the wedge-keys and drifts in the passage-ways in which they lie.

I remark that it is not absolutely essential that the keys shall be wedge-shaped. It is, however, desirable that they shall act as 25 wedges, because otherwise to be effective or satisfactory it would require a close fit of the key in the passage-ways 4 and 7.

Having thus described my invention, I claim as new and desire to secure by Letters 30 Patent—

1. In a crossing or frog of the kind recited, the combination of the base having the depression, the wear-plate seated in said depression and means for detachably securing said wear-plate to said base consisting of the channels in the base having the inclined inner walls, the projection on the under side of the wear-plate having the inclined sides forming with said walls of said channels passage- 35 ways extending from opposite sides of the top of said base adjacent the sides respectively of said wear-plate to approximately the longitudinal middle line thereof, the drift-receiving passage-ways extending from the top of said base to and communicating with the first-mentioned passage-ways respectively, together with the double-inclined keys within said first-mentioned passage-ways, and the drifts in said second-mentioned passage-ways, substantially as set forth.

ways extending from opposite sides of the top of said base adjacent the sides respectively of said wear-plate to approximately the longitudinal middle line thereof, the drift-receiving passage-ways extending from the top of said base to and communicating with the first-mentioned passage-ways respectively, together with the double-inclined keys within said first-mentioned passage-ways, and the drifts in said second-mentioned passage-ways, substantially as set forth.

2. In a crossing or frog of the kind recited, the combination of the base having the depression, the wear-plate seated in said depression and means for detachably securing said wear-plate to said base consisting of the channels in the base having the inclined inner walls, the projection on the under side of said wear-plate having the inclined sides forming with said walls of said channels passage-ways extending from opposite sides of the top of said base adjacent the sides respectively of said wear-plate to approximately the longitudinal middle line thereof, the drift-receiving passage-ways extending from the top of said base to and communicating with the first-mentioned passage-ways respectively, and of curvilinear form, together with the double-inclined keys within said first-mentioned passage-ways, and the curvilinear drifts in said second-mentioned passage-ways, substantially as set forth.

In testimony whereof I have hereunto affixed my signature.

JAMES E. LEWIS.
